STOKER

George N. Miller, Castalia, Ohio

Application June 3, 1947, Serial No. 752,025

4 Claims. (Cl. 110—103)

1

This invention relates to stokers, and more particularly to an automatic stoker for coal-fired boilers.

An important object of the present invention is to provide a novel form of stoking means for boilers wherein powdered or other relatively finely divided coal is fed to the fire bed of a furnace and evenly distributed thereover.

A further object is to provide such a stoker having novel means operative in conjunction with the coal feeding means for blowing the coal into the furnace to evenly distribute it over the fire bed.

A further object is to provide a stoker wherein a reciprocating pusher device is operative for moving coal in measured amounts per minute into a furnace and to blow the coal thus fed to the furnace over the fire bed in a uniform distribution of the coal.

A further object is to provide automatic stoking means of the character just referred to wherein the coal feeding and distributing devices are automatically simultaneously operative.

A further object is to provide a coal distributing jet blower mechanism for a stoker wherein the jet devices employed are capable of relative adjustment so as to uniformly blow the coal over the fire bed to provide a uniform distribution of the coal even for deep furnaces having relatively long grates and fire beds.

A further object is to provide a novel coal feeding mechanism in the form of a reciprocating pusher operative over a wear plate which is detachable and replaceable with a new plate after substantial wear has taken place.

A further object is to provide novel means operative independently of the automatic parts of the apparatus for determining the rate of feeding the coal to the furnace.

Other objects and advantages of the invention will become apparent during the following description.

In the drawings I have shown one embodiment of the invention. In this showing

Figure 1 is a vertical sectional view through the stoker and adjacent parts of a furnace, parts being shown in elevation and parts being broken away.

Figure 2 is a horizontal sectional view on line 2—2 of Figure 1, parts being broken away.

Figure 3 is a plan view of the stoker mechanism per se, portions of the furnace wall and the stoker feed tube being shown in section and parts being broken away.

Figure 4 is an inside face view of a portion

2

of the front furnace wall showing portions of the stoker apparatus.

Figure 5 is a detail perspective view of the pusher feed element, and

Figure 6 is a detail perspective view of one of the pusher guard plates.

Referring particularly to Figure 1, the numeral 10 designates a boiler furnace as a whole having a front wall 11, the boiler proper being indicated by the numeral 12. The usual grate structure 13 is arranged in the furnace and divides the space beneath the boiler into a fire box 14 and ash pit 15.

The wall 11 is provided with a suitably shaped opening 18 in the bottom of which is arranged a relatively heavy base plate 19 cored out in its bottom as at 20 and having its inner edge projecting through the opening 18 approximately to a point flush with the inner surface of the

wall 11. The base plate 19 forms the main supporting structure for the apparatus, as will become apparent, and this plate projects a substantial distance outwardly from the furnace wall 11 and is suitably supported at its outer end by means of a post or similar support 21.

The inner portion of the base plate 19 forms part of a tunnel-like structure defining a coal inlet tube, such tube further comprising side plates 25 and a top plate 26 preferably engaging the upper edges of the side plates 25 by a tongue and groove arrangement 27. The lower edge portions of the side plates 25 may extend downwardly along the outer edges of the base plate 19, as shown in Figure 4.

The outer end of the top plate 26 terminates approximately at the point 28 (Figure 1) and outwardly of such point is arranged a hopper spout 29 supporting an upper sheet metal hopper 30. The spout 29 may have its side walls 29' integral with or separate from the side walls 25, and the front and rear walls 31 of the hopper spout may be formed in any desired manner, that is, either integral with the side walls 29' or separate therefrom, etc. The outer and inner walls

31 have their lower edges terminating approximately at the points 32, thus providing openings straight through the feeding tube. The opening defined by the opening 32 remote from the furnace wall is normally closed by a gate 34 having

a hand piece 35 at its upper end to facilitate the raising and lowering of the gate, when desired. The hand piece 35 turns outwardly and in the angle between such hand piece and the gate 34 is arranged a bolt 36 passing through ears 37 carried by the side plates 29'. The bolt 36 clamps

the two side plates 29 toward each other and preferably normally holds such side plates in engagement with the edges of the gate 34. By loosening the bolt 36, raising the gate 34, and then tightening the bolt 35, the gate 34 may be held in elevated position for the purpose of cleaning out the feed tube, dislodging lump material, etc. The lower edge of the gate 34 normally operates in and is held in position by guides 38 carried by the outer ends of the side plates 25.

A control gate 40 extends between the side plates 25 adjacent the inner wall 31 of the hopper tube. The adjacent edges of the walls 30 are provided with ears 41 connected by a bolt 42 to 15 clamp such edges of the side plates toward each other and into engagement with the edges of the gate 40. Thus the gate 40 may be clamped in adjusted positions with its lower edge at the desired elevation to predetermine the rate of feeding of the coal to the furnace, in a manner to be described. The upper end of the gate is provided with a hand piece 43 to facilitate moving the gate 40 to vertically adjusted positions while the bolt 42 is loosened.

The outer edge 28 of the plate 26 forms with the gate 40 an opening 44 through which access can be had to the interior of the feeding tube. This opening admits air to the fire box to support combustion and the area of the opening is adjustable by a gate 45 slidable in guides 46 carried by the side plates 25.

Coal fed downwardly from the hopper into the feed tube defined by the plates 25 and 26 is adapted to be moved into the furnace by a pusher 50, shown in perspective in Figure 5 of the drawings. This pusher is preferably a single casting having a horizontal wall 51 and upstanding side flanges 52. The pusher is cored out at its underside as at 53, thus providing depending flanges 54 throughout the edge of the pusher, the forward or operating edge 55 of the pusher being flat, as shown in Figures 1 and 5. At its outer end, the pusher is provided with an upstanding flange 57 bifurcated as at 58 for a purpose to be described.

The pusher may operate directly over the top of the base plate 19, but a wear plate 60 preferably is arranged over the base plate 19 and projects outwardly beyond the pusher to be secured by screws or the like 61 (Figure 3) to the base plate 19. As the plate 60 becomes badly worn, the screws 61 may be removed and a new plate placed in position, such plate being a simple flat plate which can be relatively cheaply manufactured, thus permitting economical replacement to be made. The pusher 50 has the bottom edges of its side flanges 54 operable over the wear plate 60, as will be apparent.

To prevent powdered or other finely divided coal from spilling over the edges of the pusher 50 and thus tending to interfere with the operation of such member, guard plates 65 are employed, one of these members being shown in perspective in Figure 6 of the drawings. Each of these plates comprises a top flange 66 apertured as at 67 to receive screws or the like (not shown) for attaching the guard plates to the adjacent side plates 25. Each guard plate further comprises an inwardly extending shoulder 68 terminating in a downwardly extending flange 69 overhanging the adjacent flanges 52 of the pusher 50.

A motor is employed for reciprocating the pusher 50. In the present instance, such motor

is shown in the form of a small conventional steam engine 72 having a steam chest 73 controlling the operation of the piston (not shown) of the engine. Such piston has a conventional piston rod 74 provided with a coupling 75 comprising a pair of discs engageable against opposite sides of the flange 57 to transmit reciprocating motion to the pusher.

In practice, a conventional mechanical lubricator 78 is preferably connected to the motor or engine 72 and is operable by a rocking crank 79 connected as at 80 to one end of a link 81. The opposite end of this link is connected by a pin 82 to the pusher 50, the latter being provided with an opening 83 (Figure 5) for connection of the pin 82 thereto.

Steam for operating the engine 72 is tapped from the boiler 12 through a pipe 85 (Figure 1). This pipe leads to a conventional off-and-on regulator 86 having a weighted arm 86' to determine its operating pressure. The regulator 86 is of such type that it opens upon a drop in pressure in the boiler 12 to permit the flow of steam through the pipe 85, and cuts off the flow of such steam when the boiler pressure rises above such predetermined pressure.

From the regulator 86 a supply pipe 87 extends downwardly and is provided with a suitable fitting 88 leading to a pipe 89 connected to the steam chest 73, and a valve 90, acting as a throttle valve for the engine 72, is arranged in the pipe 89. The fitting 88 is also suitably connected by a pipe 92 to a steam manifold 93 (Figure 2), for a purpose to be described. It will be apparent that the engine 72 operates when steam is supplied through pipe 87, to effect reciprocation of the engine piston and thus reciprocate the pusher 50.

Beneath and parallel to the base plate 19 is arranged a plurality of pipes for supplying steam to the fire box to distribute coal fed to the furnace by the pusher 50. In the present instance, these pipes have been shown as being four in number, the outer two pipes being indicated by the numeral 96 and the inner two pipes being indicated by the numeral 97. Each of these four pipes is provided with a manually controlled valve 98, and the pipes 96 are directly tapped into the steam manifold 93.

For each of the pipes 97 there is provided a sleeve 99 through which such pipe extends, each sleeve 99 being provided with a suitable packing gland 100. This arrangement is provided in order that the two pipes 97 may be axially adjusted, for a purpose to be described, and it will be apparent that each pipe 97 extends into the manifold 93 to be supplied with steam therefrom.

Each of the pipes 96 and 97 extends through a metal sleeve 103 built into the furnace wall 11, and the inner ends of each of the four pipes terminates in a nozzle 104. Separate nozzles may be connected to the pipes 96 and 97, but in practice I have found it fully practicable merely to flatten the ends of the pipes 96 and 97, as shown in Figures 2 and 4 whereby each nozzle is provided with a narrow elongated discharge orifice 105 (Figure 4). In order to provide for even distribution of the fuel laterally of the grate as well as longitudinally thereof, the nozzles 104 are curved outwardly from the center line of the furnace, as shown in Figures 2 and 3.

The pipes 96 and 97 are preferably arranged in a common horizontal plane. Just beneath such plane and within the fire box 14 is arranged a distributing plate 108 preferably in the form of a

bracket having a depending flange 109 secured to the furnace wall 11. The top 110 of the distributing plate forms the operating surface thereof and is preferably semi-circular in shape, as shown in Figure 2.

Operation

Assuming that the furnace is in operation and the steam pressure in the boiler is above the predetermined point referred to, none of the parts of the present apparatus will be in operation. As soon as such pressure drops below the predetermined point referred to, the regulator 86 will admit steam from the boiler 12 through pipe 85 and through pipe 87 to be distributed to the engine 72 and manifold 93 through the various connections thereto. The engine 72 will then start to operate to slowly reciprocate the pusher 50, the speed of operation of the engine 72 being controlled by the throttle valve 90. Coal will be fed into the horizontal feed tube and on to the pusher 50, and each inward movement of such pusher carries coal toward the fire box and permits the dropping of more coal on the outer portion of the pusher. At each outward movement of the pusher 50, that is, movement toward the engine 72, the gate 34 prevents any retractive movement of the coal and accordingly the pusher will slide beneath the coal thereon. Each inward movement of the pusher therefore will result in the feeding of coal into the fire box to be dropped to the distributing plate 108.

During the continuation of such operation, steam will be supplied to the manifold 93 and will flow from such manifold in constant streams through the pipes 96 and 97 to be discharged from the nozzles 104 thereof. These nozzles having elongated relatively flat orifices, the steam jets will spread in a fan-like fashion and will blow the finely divided coal from the top surface 110 of the distributing plate. Thus the coal will be blown into the furnace and fanned out over the bed of coals. The coal will be fed to the greatest extent toward the center of the top surface 110, that is, in the region on the nozzles 104 of the pipes 97. These pipes, therefore, affect the greater percentage of the coal and the necessary quantities of coal will be blown by the center nozzles toward the back or remote end of the fire box. To properly distribute the coal throughout the length of the fire box, the pipes 97 are axially adjustable to blow the proper percentage of coal rearwardly into the furnace. Such axial adjustment of the pipes 97 adjusts the position of the nozzles 104 of such pipes, one adjusted position of each of such nozzles being shown in dotted lines in Figure

2. All of the pipes 96 and 97 may be made adjustable, but in practice I have found that it is unnecessary to adjust the outer pipes 96, the proper adjustment of the pipes 97 and their associated nozzles taking care of the requirements of furnaces of any depth. The longitudinal adjustment of the nozzles 104 assures the even distribution of fuel over the grate from front to back, while the curvature of the nozzles away from the center line of the furnace assures proper lateral distribution of the coal.

As soon as the boiler pressure has been brought up to the proper predetermined point, the regulator 86 will cut off the supply of steam to the engine 72 and to the distributing nozzles 104, and accordingly the apparatus becomes inoperative. The operation is automatically resumed whenever the boiler pressure drops below the predetermined point referred to.

The apparatus is relatively simple in construc-

tion and all parts are readily accessible for replacement and repair. For example, the bolt 36 may be loosened and the gate 34 elevated if it becomes necessary to dislodge impacted lumps of

5 coal within the feed tube, or if it becomes necessary to gain access to the interior of such tube for any other purpose. The wear caused by reciprocation of the pusher 50 takes place on the plate 60, and as previously stated, such wear plate is removable by taking out the two screws 61 (Figure 3).

The feed tube defined by the elements 25, 26 and 19 may be formed integral but it is more practicable to form them as shown in Figure 4 because of ease and economy in manufacture, and ease of assembly and replacement if the latter becomes necessary. The upper edges of the plates 25 are maintained properly spaced by the tongue and groove arrangement 27, and the lower ends 20 of the plates 25 are held in position by the lateral extremities of the base plate 19. It is not otherwise necessary to secure the elements in position, and quite obviously these elements may be cheaply manufactured and easily assembled.

25 The guard plates 65 serve to prevent coal from overflowing the edges of the pusher 50 and becoming lodged adjacent the lateral edges of or beneath the pusher, thus maintaining the latter in proper operating condition.

30 The gate 49 and the proper operation of the throttle valve 90 determine the rate at which coal is fed to the furnace. The throttle 90 controls the speed of operation of the engine 72, while the gate 40 controls the depth of the body

35 of coal being moved toward the fire box by the pusher. Thus coal may be supplied at any desired rate to the furnace. The distribution of the coal thus fed to the furnace is controlled by axial adjustment of the pipes 97 and by the proper controlling of the valves 98 to supply

40 steam at the desired rate to the nozzles 104. Through proper adjustment to the various parts referred to, coal may be supplied at the desired rate to the furnace for most efficient operation, and the coal may be perfectly distributed over the fire bed. Having properly adjusted all of the parts referred to, the apparatus thereafter is fully automatic in operation without any attention.

45 50 The usual draft means (not shown) for the furnace is controlled in any conventional manner, and the opening 44 (Figure 1) provides for the admission of secondary air to the fire box 14 to properly support and complete the combustion of the fuel.

55 I claim:

1. A furnace having a fire box and a grate therein, and a front wall provided with a horizontal opening above the level of the grate, a coal supply tube communicating with the fire box through the opening in said front wall, a hopper outwardly of said wall, a hopper tube communicating between said hopper and said coal supply tube for supplying relatively finely divided coal to the latter, said hopper tube having one vertical wall nearest the wall of the furnace arranged for vertical movement to predetermine the depth of the coal in said supply tube, a horizontal pusher horizontally reciprocable in said supply tube to move coal into the fire box at each inward reciprocation of such pusher, a motor for reciprocating said pusher, said pusher having upstanding flanges along its longitudinal edges, and stationary flanges carried by the sides of said coal supply tube and projecting downwardly over

the upper edges of the flanges of said pusher to minimize the dropping of coal over the edges of said pusher.

2. A steam boiler having a boiler unit, a fire box, a grate, and a front wall provided with a horizontal opening therethrough above the grate, a coal supply tube communicating with the fire box through the opening in said wall and projecting outwardly therefrom, a hopper, a vertical hopper tube for supplying relatively finely divided coal from said hopper to said supply tube, a horizontally reciprocable pusher in said supply tube operable upon each inward reciprocation thereof for supplying coal to said fire box, a steam engine for reciprocating said pusher, a distributing plate carried by said front wall of the furnace and projecting inwardly therefrom above the grate and below the opening through such wall and onto which coal falls from said supply tube, a plurality of fluid pressure tubes projecting horizontally through the front wall and terminating in discharge nozzles over said distributing plate, means operable upon a predetermined drop in pressure in said boiler unit for supplying steam to said engine and to said fluid pressure tubes, and means for controlling said engine independently of the supply of steam to said fluid pressure tubes.

3. A steam boiler having a boiler unit, a fire box, a grate, and a front wall provided with a horizontal opening therethrough above the grate, a coal supply tube communicating with the fire box through the opening in said wall and projecting outwardly therefrom, a hopper, a vertical hopper tube for supplying relatively finely divided coal from said hopper to said supply tube, a horizontally reciprocable pusher in said supply tube operable upon each inward reciprocation thereof for supplying coal to said fire box, a steam engine for reciprocating said pusher, a distributing plate carried by said front wall of the furnace and projecting inwardly therefrom above the grate and below the opening through such wall and onto which coal falls from said supply tube, a plurality of fluid pressure tubes projecting horizontally through the front wall and terminating in discharge nozzles over said distributing plate, a manifold communicating with said fluid pressure tubes, means operable upon a predetermined drop in pressure in said boiler unit for supplying steam to said engine and to said manifold, and means for controlling said engine inde-

pendently of the supply of steam to said manifold.

4. A furnace having a fire box and a grate therein, and a front wall provided with a horizontal opening above the level of the grate, a coal supply tube communicating with the fire box through said horizontal opening, means for supplying coal to said tube, a pusher horizontally reciprocable in said supply tube to move coal into the fire box at each inward reciprocation of said pusher, an engine for reciprocating said pusher, a distributing plate projecting into the fire box from said front wall above the level of the grate, a fluid pressure tube projecting through said furnace wall and terminating in a discharge nozzle arranged over said distributing plate, a source of pressure fluid supply, a conduit connecting said source to said fluid pressure tube, means in said conduit for controlling the supply of pressure fluid therethrough, a pipe connecting said engine to said conduit between said control means therein and said fluid pressure tube, and means in said pipe for controlling the speed of operation of said engine.
